WILLIAM PERRY TAYLOR, OF BUFFALO, NEW YORK.

COVER-FASTENING FOR STOP-COCK BOXES.

1,157,062.

Specification of Letters Patent. Patented Oct. 19, 1915.

Application filed May 13, 1914. Serial No. 838,300.

To all whom it may concern:

Be it known that I, WILLIAM PERRY TAYLOR, a citizen of the United States, residing at Buffalo, in the county of Erie and State 5 of New York, have invented new and useful Improvements in Cover-Fastenings for Stop-Cock Boxes, of which the following is a specification.

This invention relates to means for fastening 10 a cover, cap or closure over the end of a pipe and more particularly to a fastening device for the covers of stop cock boxes or pipes.

It is the object of this invention to provide 15 a fastening for the covers of such pipes or boxes which can be produced at comparatively low cost, which permits the cover to be easily and conveniently applied to or removed from the box, and which will securely 20 hold the cover on the box and prevent the same from becoming displaced by frost or otherwise.

In the accompanying drawings: Figure 1 is a vertical section of a stop cock box or 25 pipe having its cover secured thereto by my improved fastening. Fig. 2 is a detached side elevation of the cover equipped with part of the fastener containing my invention. Fig. 3 is a horizontal section taken in 30 line 3—3, Fig. 1, looking upwardly.

Similar characters of reference indicate corresponding parts throughout the several views.

The stop cock box or pipe 1 may be of any 35 suitable construction but as shown in the drawings the same is made of cast metal in the usual and well known way and provided at its upper end with an annular upwardly projecting flange 2, an external upwardly 40 facing shoulder 3 at the base of said flange and a locking lug 4 projecting inwardly from one part of the bore of the pipe adjacent to its upper end.

5 represents the disk or body of the cover 45 of the box or pipe which is adapted to rest with its underside against the upper edge of the pipe flange 2 and provided with a downwardly projecting annular flange 6 which surrounds the pipe flange in the closed position of the cover, as shown by full lines in Fig. 1.

Projecting downwardly from the central part of the underside of the cover disk is a depending shank or neck 7 which is prefer-

ably constructed in the form of a hollow cylindrical tube for the purpose of making the same light and reducing the amount of metal used in the same. On the lower part of the periphery of this neck the same is provided with a clamping screw thread 8 beginning preferably at the lower end of the neck and extending upwardly around the same at least one turn, preferably about one and two thirds turns, as shown in the drawings. The peripheral diameter of this 60 thread is less than the distance from the inner end of the locking lug 4 and the diametrically opposite part of the bore of the stop cock box or pipe.

For the purpose of attaching the cover 70 to the box its threaded shank is first passed downwardly into the box or pipe through the space between the inner end of the locking lug and the diametrically opposite part of the box, as shown by dotted lines in Fig. 75 1, at which time the cover, neck and screw thread are arranged eccentrically or axially out of line relatively to the axis of the box. After the cover has been lowered sufficiently 80 to bring a part of its screw thread below the locking lug of the box and while the flange of the cover is still above the flange of the box, the cover is moved laterally so that the same is in axial alignment with the box and a part of the screw on the neck is arranged 85 underneath the locking lug. When the cover is in this position the same is rotated in the direction for causing the screw 90 thread by wedging engagement with the locking lug to draw the cover downwardly until the underside of the cover engages with the upper end of the box flange and the cover flange surrounds the box flange, as shown by full lines in Fig. 1. By this means the cover can be securely tightened 95 and reliably held in place on the box so that the same cannot be lifted or broken by frost or otherwise. The removal of the cover from the box is effected in a manner reverse 100 to the operation just described for applying the same to the box.

For the purpose of shifting the cover, neck and thread laterally positively in a direction for engaging a part of the thread underneath the locking lug when the neck has 105 been lowered a sufficient extent in the box means are provided which preferably consists of a shifting lug 9 arranged on the

inner side or bore of the box diametrically opposite to the locking lug and on a line below the same and provided with an inclined face 10 at its upper end. Upon lowering the neck and screw in the box a part 5 of this thread engages with the inclined face of the shifting lug causing the neck, cover and thread to be shifted laterally for bringing these parts axially in line with the box and carrying a part of the thread underneath the locking lug. This shifting lug therefore insures moving of the clamping 10 thread into engagement with the locking lug at the proper time and facilitates applying the cover to the box.

While the cover is screwed down fully on the box the interlocked flanges of these members prevent the cover from moving laterally relatively to the box, thus confining 20 the screw thread underneath the locking lug and preventing accidental detachment of the cover from the box.

The cover and its flange, neck and thread are preferably cast in one piece for cheapness of manufacture and the same may be turned in either direction for tightening or loosening the same on the box by any suitable means but preferably by means of a spanner wrench adapted to engage with 30 notches 11, 11 formed on diametrically opposite sides of the cover.

The length of the neck 7 and the diameter of the thread 8 of the pipe closure and their construction and proportion relatively to the 35 pipe 1 and the locking lug 4 are such that the initial engagement of said thread with the underside of the locking lug may be affected by inserting the shank and thread into the pipe while the same and the disk 5 and flange 6 are tilted relatively to the pipe, after which the parts of the closure may be shifted into an upright concentric position relatively to the pipe and the closure secondly fastened to the pipe by turning the 45 same forwardly, so that the screw by working against the lug 4 will draw the disk 5 and flange 6 against the end of the pipe.

I claim as my invention:

1. A cover for a pipe having an internal 50 locking lug on one side of its bore while the opposite side of said bore is unprovided with a locking lug, comprising a disk adapted to extend over the upper end of the pipe, an annular depending flange adapted to engage 55 with the outer side of said pipe, a shank depending from the underside of the disk and adapted to extend downwardly along the inner end of said lug, and a screw thread arranged on the exterior of said shank and 60 extending at least one complete turn circumferentially around the same, the peripheral diameter of said thread being less than the distance from the inner edge of said locking lug to the diametrically opposite 65 part of the bore of the pipe, said shank

and thread being movable downwardly between said lug and the opposite side of the pipe and then laterally for engaging said thread with said lug before said flange engages with the periphery of said pipe.

2. The combination of a pipe provided on one side of its upper end with an internal locking lug and on its opposite side below the plane of the locking lug with a shifting lug having an inclined face which slopes 75 inwardly and downwardly, and a cover comprising a disk adapted to extend over the top of the pipe, a shank depending from the disk, and a screw thread arranged on the exterior of said shank and adapted to engage with the 80 inclined face of said shifting lug and to be moved laterally thereby so as to engage another part of said thread with the underside of said locking lug.

3. The combination of a pipe having a 85 flange at its upper end and a locking lug on one side of its bore, and a cover having a disk extending over the top of said pipe, an annular flange surrounding the flange of the pipe, a shank depending from said disk, and 90 a screw thread extending at least one turn around the shank and engaging the underside of said locking lug, the peripheral diameter of said thread being less than the distance from the inner end of said lug to the 95 diametrically opposite part of the bore of said box, said shank and thread being movable downwardly between said lug and the opposite side of the pipe and then laterally for 100 engaging said thread with said lug before said flange engages with the periphery of said pipe.

4. The combination of a pipe having a flange at its upper end, a locking lug on one side of its bore, a shifting lug arranged on 105 the opposite side of the bore of the box below the plane of the locking lug and having an inwardly and downwardly inclined face, and a cover having a disk extending over the top of said pipe, an annular flange surrounding the flange of the pipe, a shank depending from said disk, a screw thread extending at least one turn around the shank and engaging the underside of said locking lug, the peripheral diameter of said thread 110 being less than the distance from the inner end of said lug to the diametrically opposite part of the bore of said pipe, and a part of said thread on one side of said shank being adapted to engage said inclined lug for 115 shifting a part of the thread on the opposite side of the shank underneath said locking lug.

5. The combination of a pipe provided on one side of its bore adjacent to the outer end 120 thereof with an inwardly projecting locking lug, and a cover having a disk adapted to extend over the outer end of the pipe, a marginal flange adapted to engage the periphery of the pipe, a shank projecting from 125

the underside of said disk into the pipe, and a screw thread arranged on the outer side of said shank and adapted to engage with the underside of said lug, said shank being of such length and said thread being of such diameter that the initial engagement of said thread with the underside of said lug may be effected by inserting the shank and thread

into the pipe while the same and the disk and flange are tilted relatively to the pipe. 10

Witness my hand this 11th day of May, 1914.

WILLIAM PERRY TAYLOR.

Copies of this patent may be obtained for five cents each, by addressing the "Commissioner of Patents, Washington, D. C."

It is hereby certified that in Letters Patent No. 1,157,062, granted October 19, 1915, upon the application of William Perry Taylor, of Buffalo, New York, for an improvement in "Cover-Fastenings for Stop-Cock Boxes," an error appears in the printed specification requiring correction as follows: Page 2, lines 43-44 for the word "secondly" read *securely*; and that the said Letters Patent should be read with this correction therein that the same may conform to the record of the case in the Patent Office.

Signed and sealed this 9th day of November, A. D., 1915.

[SEAL.]

J. T. NEWTON,

Acting Commissioner of Patents.
